(21) Appl. No.: **29/262,066**

(57) **CLAIM**

(22) Filed: **Jun. 26, 2006**

The ornamental design for an envelope for a light bulb, substantially as shown and described.

(51) **LOC (8) Cl.** **26-04**

DESCRIPTION

(52) **U.S. Cl.** **D26/2**

FIG. 1 is an elevational view of a first side of the envelope of the invention;

(58) **Field of Classification Search** D26/1-4;

FIG. 2 is an elevational view of a second side of the envelope of the invention rotated 90 degrees;

313/313, 315, 317, 318, 493; 315/52, 53,

FIG. 3 is a plan view of the envelope of the invention; and,

315/56, 57, 58

FIG. 4 is a top view of the envelope of the invention.

See application file for complete search history.

The elements for which the design is claimed are shown in solid lines.
